The design for a bottle, as shown and described.

DESCRIPTION

FIG. 1 is front view of a bottle showing my design, the rear view, left side view and right side view being identical thereto;

FIG. 2 is a bottom view thereof; and,

FIG. 3 is a bottom-front perspective view thereof.

In the drawings the dash-dot-dash broken lines represent the boundary of the claimed design and form no part thereof. The dash-dash broken lines depict environmental subject matter in which the claimed design is embodied and form no part of the claimed design.
